Homer Arthur King.

UNITED STATES PATENT OFFICE.

HOMER ARTHUR KING, OF COLTON, CALIFORNIA.

TWIN-HEAD ROTARY ENGINE.

No. 813,974.

Specification of Letters Patent.

Patented Feb. 27, 1906.

Application filed August 5, 1905. Serial No. 272,927.

To all whom it may concern:

Be it known that I, HOMER ARTHUR KING, a citizen of the United States, residing at Colton, in the county of San Bernardino and 5 State of California, have invented a new and useful Rotary Engine, of which the following is a clear and exact description.

My invention relates to improvements in rotary engines in which I employ trailing 10 cylinder-heads or cylinder-head in an annular cylinder.

The object of my invention is to supply a simple and safe substitute instead of those complicated dangerous cylinder-heads which 15 enter and are withdrawn from the cylinder to let the pistons pass. I attain this object and increased speed with economy of motive fluid and weight by mechanism illustrated in the accompanying drawings, making a part of 20 this specification, in which similar characters of reference indicate corresponding parts in all the figures.

Figure 1 is a vertical section of the inner exhaust side of my engine. Fig. 2 is an elevation of the piston-disk. Fig. 3 is a vertical section showing the inner part of the side of the annular cylinder of my engine with ports for admitting the motive fluid and with Fig. 2 in place, but with two cylinder-heads F F locked to the cylinder and pistons E E driven forward as if the parts were all in place and in operation. Fig. 4 is a vertical section of the annular cylinder corresponding to Fig. 1, but with more exhaust-openings H 35 and H'. Fig. 5 is an elevation corresponding to Fig. 2, but with this central disk having more twin heads E F. Fig. 6 is a vertical section corresponding to Fig. 3, but with more twin pistons and cylinder-heads and 40 with two cylinder-heads F F just unlocked and hastening to their normal place near E. Fig. 7 is an elevation of the exhaust-regulator L' shown in Fig. 8, but probably will not be needed. Fig. 8 is a vertical cross-section of 45 my engine with all the parts in place, taken in line through F F. Fig. 9 is an elevation of the cut-off L, with slots to correspond with the number of pistons in style Fig. 6. Fig. 10 is a cross-section of one of the cylinder-heads F, taken in the line where the two halves of the cylinder are united by bolts through 50 the periphery. Fig. 11 is a cross-section of one of the pistons E, taken in line of cross-section of the annular cylinder.

55 The letter A refers to the exhaust side of

the annular cylinder, through which the used motive fluid escapes by port-holes H and H'.

B refers to the side where the motive fluid is admitted through port-holes I.

C designates the disk to which pistons E 60 are secured by bolt E'.

D is the opening for the shaft D'.

F is the trailing cylinder-head connected by wire J to piston E, each end secured in a cavity bringing E and F nearer together, and 65 F' is the flexible face which yields to the pressure of the motive fluid and locks bolts F' in depressions in the cylinder at desired points.

G is the outside casing forming the exhaust-chest with port-hole, and G' is the casing forming the motive-fluid chest. 70

K is a depression near the periphery of the flange for packing.

N indicates the usual collar-ring with an opening for contraction or expansion. 75

When the parts are all in place and the motive fluid is admitted at I I between the heads E F E F, F F are locked by pressure on faces F' F', forcing bolts F' F' into depressions in the cylinder and forcing pistons E E 80 forward, first by direct pressure while slots M M are over I I and when covered then by expansion, and before E E reach exhausts H H, Fig. 6, two other pistons have passed two other port-holes I I, and direct pressure is on 85 again. When the used motive fluid escapes at H H', any remaining escapes at ports H' giving constant pressure; but when style Figs. 1, 2, and 3 is used and the expansion is caused by explosion, both E and F are 90 allowed to pass I I ere the sparks cause the explosion. The momentum carries the pistons forward, so that constant pressure is not needed; but it can be had even in this style by arranging two or more engines on one 95 shaft or axle.

The heads E and F may be connected by two or more coiled-wire springs, or one of less coiled diameter may be used in one of larger diameter, or any other elastic connection 100 may be used.

What I claim as my invention, and desire to secure by Letters Patent, is—

1. One or more pistons and trailing cylinder-heads, within an annular cylinder of a 105 rotary engine, connected to a disk and shaft revolved by the pressure of a motive fluid.

2. One or more pistons and trailing cylinder-heads having a cavity in each of the latter or in all, in which the ends of an elastic 110

connection are secured, and a disk to which the pistons are secured within an annular cylinder of a rotary engine revolving a shaft by pressure of a motive fluid.

- 5 3: Within the annular cylinder of a rotary engine, a piston, a trailing cylinder-head having elastic connection therewith, with bolts movable by the pressure of a motive fluid, automatically locking the cylinder-head to the cylinder, and automatically unlocking it by the diminishing pressure and elastic connec-

tion to the piston, said piston being secured to a disk revolving a shaft by the pressure of a motive fluid.

In testimony whereof I have signed my name to this specification in the presence of two subscribing witnesses.

HOMER ARTHUR KING.
